AUTOMATIC TRAIN-ORDER DELIVERER TO MOVING TRAINS

Application filed September 19, 1929. Serial No. 393,689.

This invention relates to improvements in apparatus for safety automatic delivery of messages and train orders to moving trains and the like.

5 One object of the invention is to provide a simple and effective means for delivering orders, messages, etc. without stopping the train.

Another object is to provide such means as 10 may be operative when the train is moving in either direction.

Another object is to overcome the hazardous position of an operator standing on the ground and attempting to deliver train orders while the train is moving.

15 A further object of the invention is to provide means for preventing or eliminating an obstruction when the apparatus has delivered the message or order, automatically 20 swinging to a released position and dropping in a suitable receptacle below the ground.

Further objects will be apparent from the following description as illustrated in the accompanying drawings, in which,

25 Fig. 1 is a side elevation showing the signal lights in relation to the train order post and an oncoming train.

Fig. 2 is view of the box broken away to 30 show the post in position for delivering the message.

Fig. 3 is a side view of the post shown in Fig. 2.

Fig. 4 is an enlarged view of the upper 35 part of the post showing the hoop with message in position.

Fig. 5 is a side view of the box broken away to show the cradle into which the post is dropped when a message or order is delivered.

40 Fig. 6 is a detail view of the hinge portion of the post.

Fig. 7 is a side elevation of the hoop.

Fig. 8 is bottom view showing the diagonal 45 cut in the hoop.

Fig. 9 is a view of the cap used for the single throw.

Fig. 10 is a side view of Fig. 9.

Fig. 11 is the three point spring and stud 50 bolt in section.

Fig. 12 is a top view of Fig. 11 with spring stop plate locking device.

Fig. 13 is side view of the spring stop plate locking device.

Fig. 14 is the contact spring for three way 55 signal light.

Fig. 15 is the spring support for the signal light at the post.

Fig. 16 is a plan view of the three point 60 spring.

Fig. 17 is a perspective of the three point spring showing the spring broken, the plate and the special nut.

Fig. 18 is an enlarged perspective of the 65 three point spring.

Referring to the drawings:

The base of the post 1 is preferably of cement and rising upwardly therefrom is a column 2 which is hollow and fastened by suitable means thereon is a steel plate 3 and 70 fibre plate 4. Also a stud bolt 5 supports a three point spring 6 on steel plate 3. The three point spring holds the order delivery post in upright position by means of special nut 7 and stop plate 8. Vertical and horizontal slots 9 and 9A in stud bolt 5 are for the purpose of lubricating spring 6.

The lower half 10 of a hinge joint is fastened in the hollow portion of column 2 by suitable means such as welding or the like, 80 and the upper half 11 of the hinge joint is pivoted on hinge pivot 40 on the lower portion, the upper portion being fastened to column or post 12 by suitable means such as welding or the like.

85 The removable cap 13 is screwed on column 12 and is used to hold orders, messages, etc. by use of the hinged clamps 14 and 14A which hold split hoop 16 in delivery position. Cap 13 also is equipped with finger rings 15 and 15A for opening hinge clamps 14 and 14A to insert split hoop 16 on the top of which are spring clips 17 for holding the orders, messages, etc. which are detached from the delivery post by means of a train man's arm passing through split hoop 16 placed on the side nearest the approach of the train, which causes the clamp 14 to open, and the force of the impact or pull as the hoop 16 is withdrawn from the clamp while the train is in motion 95 100

causes the column or post 12 to be knocked down or dropped in the direction of movement, in the box 45 which is buried in the ground and closes covers 46-47 or 47-48 as is desired.

Spring 18 and spring adjusting screw 19 are used for holding hinge clamps 14 and 14A together and at the correct tension when split hoop 16 is in place.

10 Tension spring 20 is used for centering the column 12 if the three point spring 6 should become inoperative and is fastened to the lower half of hinge joint 10 by means of a link 23 and is held in place at its upper end by tie rod 21 looped over pin 22 which is journaled in column 12, the spring 20 expanding and contracting in column 12 and hinge portion 11 which is hollowed, for that purpose.

15 A contact spring 24 is mounted at the side of the post on a fibre plate 4 and is used for opening and closing contact points 25 and 25' as fibre wheel 27 supported on shaft 28 by retaining screw 29 passes over boss 26 on contact spring 24. The shaft 28 is held in position at all times by means of a weld to column 12.

20 The centering key 30 is fastened to column 12 by suitable means such as welding or the like and is used for holding the delivery post in an upright position by engaging spring 6. Guide 31 is for holding contact spring 24 in place and to insure its stopping at correct opening position and is fastened to fibre plate 4 by lock nuts 32.

25 Spring support 33 may be used as a shock absorber for bracket 34 and signal light 35 which may be attached to it as shown in Fig. 3.

30 Signal lights 35 and 35A form a three way signal for the purpose of notifying train men of an order present and also for illuminating hoop 16.

35 For a single throw post, cap 36 and hoop clamp 36A are used, instead of the cap 13.

40 The bumper blocks 37 and 37' with pads 38 of a resilient material such as rubber, and a pair of springs 57 and 57' fastened at the upper end through pads 38 to bumper blocks 37 and 37' and riding on plates 58, are used 45 to take up the shock as the post falls into reclining position in box 45, incident to the throw of the post as the hoop 16 is withdrawn from its position on the delivery post. The post in falling contacts with pad 38 which pushes trip lever 43 suspended by spring 69, downward, which in turn rotates trip lever 44 forward on shaft 42 touching trip pin 49 which causes levers 50 and 51 to pivot at 85 and 85' thus dropping covers 46 and 47 or 47 and 48 to the closed position. Either of the 55 cover sections 46 or 48 may be latched to the intermediate cover section 47 by simple pivoted latch 79 or 80. In Fig. 1 the sections 46 and 47 are shown in open position with the 60 latch 79 engaged, since the approach of the 65

train is in the direction to swing the post 12 down to the left, the section 48 being closed. Its position when open is indicated in dotted lines.

70 Shaft 42 is supported in steel plates 41 and 41' on each side of bumper block 37, near each end of box 45. Box 45 is to be extended lengthwise to accommodate the delivery pole if used for both directions of throw.

75 If bracket 34 is used outside of box 45 an insulating plate 56 should be used as shown in Fig. 1. Display signal 83 is to be operated together with signal light 35 and 35A but one mile west for east approaching trains to signify an order ahead.

80 Display signal 84 is used the same way only for west approaching trains, as by throwing a knife switch in the signal circuit.

85 The stud bolt boss 5a is grooved at 60 for spring point 6c, and special nut 7 is slotted at 65 and 66 for the two upper points 6a and 6b of the spring 6.

90 The three point spring 6 has three contact points 6a, 6b and 6c and is used in connection with centering key 30 to hold or center the post in an upright position. The two top spring points 6a and 6b are on opposite sides of the centering key 30. Then as the post 12 strikes either top spring 6a or 6b in dropping, it rotates spring 6 and causes the bottom spring point 6c to jump from the groove 60 in the collar 5a which encircles the stud bolt 5 at the base of the spring 6.

95 The top spring points 6a or 6b also jump from grooves or slots 65 or 66 as the post 12 is released.

100 If the spring tension is too weak when point 6a engages groove or slot 66, turn nut 7 down until either 6a or 6b engages groove or slot 65, to hold the post 12 in an upright position.

105 The stop plate 8 is to prevent the spring points 6a and 6b from going beyond a set point, and is for use only when one way service is used. It is fastened to nut 7 by screws 7a and 7b.

110 The bottom of box 45 should have drainage holes in case of rain or snow when the box is open. As many changes could be made in the above construction and many widely different embodiments of our invention within the scope of the claims, constructed without departing from the spirit of the scope thereof, it is intended that all matter contained in the accompanying specification and drawings shall be interpreted as illustrative and not in a limiting sense.

115 We claim:

120 1. In a train order delivery apparatus, the combination with a support, of a pivoted post thereon provided with a holder, and a spring latch device engageable with the post to hold the same in upright position, and reversible in either direction.

2. The combination stated in claim 1, said latch device including a stud and a spring rotatable thereon, said spring having a pair of projections engaging opposite sides of the post when in upright position.
- 5 3. The combination stated in claim 1, said device including a stud, and a spring coiled around the same, the spring having a pair of opposite points at the top and a single point at the bottom having a slip engagement with the stud, whereby the spring may turn on the stud when the post is swung down in either direction.
- 10 4. The combination stated in claim 1, said latch device including a stud and a spring coiled around the stud and having a slip engagement therewith, and a nut on the stud to confine the spring, said nut having a projection to set the end of the spring.
- 15 5. In a train order delivery apparatus, the combination with a support and a pivoted post thereon provided with a holder, and adapted to swing from vertical to horizontal position, of a bumper against which the post
- 20 strikes when swung down, a hinged cover plate adapted to swing down over the post when it strikes the bumper, and a trip device actuated by the post and connected with the cover to close the latter.
- 25 6. The combination stated in claim 5, said trip device comprising a lever and link connection to the cover, the lever being located adjacent the bumper.
- 30 7. The combination stated in claim 5, the trip device including a lever extending across the bumper in position to receive the impact of the post, and a link connection between the lever and the cover.
- 35 8. The combination stated in claim 1, and a signal light and circuit having contacts closed by the movement of the post to upright position.
- 40 9. The combination stated in claim 1, and a signal light and circuit controlled by the movement of the post, the signal light also having means to illuminate the holder when the post is in upright position.
- 45 10. In a train order delivery apparatus the combination with a support, of a post pivoted at the bottom thereon to swing down in either direction, said post having a pair of holders at the top, a box on each side of the post, into either of which the post may swing down, a cover for each box, and means
- 50 actuated by the post when it swings down to close the cover of the box into which the post swings.
- 55 In testimony whereof, we do affix our signatures.

60 AUGUST J. WALTERS.
NOAH B. SMITH.
